UNITED STATES PATENT OFFICE.

KARL HEILMANN, OF MAGDEBURG-BUCKAU, GERMANY, ASSIGNOR TO R. WOLF AKTIENGESELLSCHAFT, OF MAGDEBURG-BUCKAU, GERMANY, A CORPORATION OF GERMANY.

PORTRABLE OR SEMIPORTABLE STEAM-ENGINE.

1,372,430.

Specification of Letters Patent. Patented Mar. 22, 1921.

Application filed October 17, 1919. Serial No. 331,470.

To all whom it may concern:

Be it known that I, KARL HEILMANN, a citizen of Germany, residing at Magdeburg-Buckau, Germany, have invented certain new and useful Improvements in Portable or Semiportable Steam-Engines; and I do hereby declare the following to be a full, clear, and exact description of the invention, such as will enable others skilled in the art to 10 which it appertains to make and use the same.

My invention relates to improvements in portable or semi-portable steam engines, and the object of the improvements is to provide 15 a portable or semi-portable steam engine in which the engine is so mounted on the boiler, that it is independent of the expansion of the boiler by heat. With this object in view my invention consists in providing a portable or semi-portable steam engine in which the engine is supported with one part independently of the boiler and on the foundation thereof, while it is supported with another part of the boiler and through 20 25 a bearing member having an inclined bearing face which by its inclination renders horizontal and vertical expansion of the boiler ineffective as to the position of the engine. A further object of the improvements is to mount the engine in such a way that the forces caused by the reciprocating masses, such as the piston and the crank mechanism, are not transmitted to the foundation through the part which is directly 30 35 supported on the foundation, but through the boiler. With these and other objects in view my invention consists in the matters to be described hereinafter and particularly pointed out in the appended claims.

For the purpose of explaining the invention an example embodying the same has been shown in the accompanying drawings, in which the same letters of reference have been used in all the views to indicate corresponding parts. In said drawings.—

Figure 1, is a side view of the engine,

Fig. 2, is a vertical cross-section taken on the line 2—2, of Fig. 1,

Fig. 3, is a detail view showing the connection between the boiler and engine through which the forces caused by the reciprocating masses are transmitted to the boiler,

Fig. 4, is a side view of Fig. 3, and

Fig. 5, is a detail view showing a modification of the inclined bearing for supporting the engine on the boiler.

Referring to the example illustrated in the drawings, the portable or semi-portable steam engine consists of a boiler *a* which is supported on a foundation *b* by means of shoes *c*¹ and *c*². Above the boiler a steam engine is located which as shown consists of a cylinder *d*, a frame *e*, a bearing plate *f* to which the frame is secured, the crank mechanism (not shown), and the crank shaft *g*. The shoes *c*¹ are located vertically below the crank shaft, and the bearing plate *f* is rigidly connected with the shoes *c*¹ by means of uprights *h* made from sheet metal or *h*¹ 60 65 70 constructed of steel bars.

At its rear end the engine is supported on the boiler *a*. As shown in Fig. 1, the cylinder *d* is formed at its rear end with shoes *i* and to the top of the boiler a bearing plate *j* is secured. The contacting bearing faces of the shoes *i* and the bearing plate *j* are inclined downward and toward the rigid connection of the engine to the shoes *c*¹, and the angle of inclination is such that in case 80 85 of horizontal and vertical expansion of the boiler by heat the points of the bearing plate *j*, for example the point B is shifted in the direction of the bearing face and into the position B', and a point D into the position D', so that the expansion of the boiler by heat has no influence on the position of the engine, provided that the boiler is rigidly secured at A, and that the longitudinal expansion of the boiler is proportional to the length A B and the vertical expansion to the length C B. In this case 90 95 the point B is shifted in the direction A B and into the position B'. In Fig. 5 I have shown a modification in which a roller *m* is interposed between the inclined bearing members.

The steam engine is constructed in the form of a system in which the pressures from the crank mechanism are centrally taken up by the frame and are not transmitted to the boiler.

Preferably the forces caused by the reciprocating masses are not transmitted to the uprights *h* and *h*¹ but to the boiler. For this purpose sheet metal links *l*, *l*¹ are se-

cured to the boiler which engage the bearing plate *f* with their front and rear ends, as is shown in Figs. 3 and 4. The said links are disposed in the plane of the forces of the 5 movable members of the engine, and they are located vertically above the points where the boiler shoes are secured to the foundation, so that the forces caused by the reciprocating masses are transmitted to the 10 foundation within the planes in which they are produced.

In the example shown in Fig. 1 angle bars *n*, *n'* are secured to the top of the boiler in lieu of the links *l*, *l'*, and the said 15 angle bars engage guide faces provided at the front and rear sides of the plate *f*. Thereby longitudinal displacement of the plate *f* by the forces of the masses is avoided. Similar means are provided to lock the 20 plate as against transverse displacement.

I claim:

1. In an engine of the class described, the combination with the boiler, of a steam engine mounted on said boiler and having one 25 part non-shiftable and another part which is connected with the non-shiftable part shiftable relatively to the boiler, and bearing members intermediate the boiler and the shiftable part arranged to render expansion of the boiler longitudinally and 30 transversely of the engine ineffective as against the position of the shiftable part.

2. In an engine of the class described, the combination with the boiler, of a steam engine mounted on said boiler and having one 35 part non-shiftable and another part which is connected with the non-shiftable part shiftable relatively to the boiler, and bearing members intermediate the boiler and the shiftable part having their bearing faces 40 inclined toward the boiler and the non-shiftable part.

3. In an engine of the class described, the combination with the boiler secured to a foundation, of a steam engine mounted on 45 said boiler and having one part non-shiftable and another part which is connected with the non-shiftable part shiftable relatively to the boiler, and links located in the plane in which the forces of the movable 50 parts of the engine act and secured to the boiler at a point located vertically above the parts where the boiler is secured to the foundation, said links engaging the engine for preventing longitudinal displacement of 55 the engine, whereby the forces caused by the moving masses are directly taken up where they are exerted.

In testimony whereof I hereunto affix my signature in the presence of two witnesses. 60

KARL HEILMANN.
